WALL CONSTRUCTION

Frederick M. Venzie, Philadelphia, Pa., assignor
to National Gypsum Company, Buffalo, N. Y.,
a corporation of Delaware

Application August 14, 1933, Serial No. 684,965

5 Claims. (Cl. 72—46)

My invention relates to building construction and more particularly to novel paneled, interior, partition walls.

The invention comprises a wall having an all metal surface in which the studding is resiliently supported with respect to the ceiling and floor and in which the surfacing units may be erected without the use of any tools except a hammer, combined with finishing strips which cover the means used for holding the surfacing units in position and give the wall a paneled effect.

An object of my invention is to provide a partition wall which can be readily and expeditiously erected and from which is eliminated the use of all clips which are attachable, or movable, behind the wall surface.

Another object of my invention is to provide a wall comprising rigid surfacing units which units may have a final decorative coating applied thereto prior to their erection.

Another object of my invention is to provide a wall constructed of a multiplicity of metal faced panels which when erected will give the effect of a room paneled with wood.

A more specific object of my invention is to provide a novel unit capable of use as studding which is adapted to support surfacing units against movement toward the interior of the wall and which comprises means for supporting the clips to prevent the movement of the units outwardly from the plane of the wall.

A further object of my invention is to provide a unit which may be used not only as studding and to support vertical finishing strips but which may also be positioned horizontally and hold horizontal finishing strips in position.

Yet another object of my invention is to provide a wall construction in which the studding is resiliently supported with respect to vertical movement thereof while fixed against movement out of a vertical plane.

Yet a further object of my invention is to provide a wall as described which is fire-resistant in character.

Other objects and advantages of my invention will be apparent from the following specification, claims, and from the drawings, in which:

Fig. 1 is a side elevation of a wall embodying my invention;

Figs. 2 and 3 are vertical sections taken on the lines 2—2 and 3—3 respectively, Fig. 1;

Figs. 4 and 5 are horizontal sections taken on the lines 4—4 and 5—5, Fig. 6;

Fig. 6 is a vertical section taken on the line 6—6, Fig. 1;

Fig. 7 is a detail view on an enlarged scale of the upper portion of Fig. 6; and

Fig. 8 is a horizontal section taken on the line 8—8, Fig. 7.

Referring now particularly to Figs. 1 and 6, my wall is held in position by properly aligned nailing strips 10 and 11 attached to a ceiling 12 and floor 13 respectively, the nailing strips being of a width substantially equal to that of the studding 14 hereinafter referred to.

To the nailing strips 10 and 11 in vertical alignment and at suitably spaced intervals are connected as by nails 15 oppositely facing pairs of guideways 17 having channel shaped lower ends 17a the flanges of which extend inwardly with respect to the wall. The upper ends 17b of the guideway 17 are flat and adapted to lie in contact with the outer faces of the nailing strips 10 and 11.

The lower ends 17a of each pair of guideways 17 carry an expansion member 18 composed of two shells 18a each having inwardly facing flanges 18b and outwardly facing flanges 18c. The outwardly facing flanges 18c are positioned at the ends only of the expansion members, and the upper and lower flanges are adapted to fit over the nailing strip 10 and the end of the studding 14 respectively. The upper and lower inwardly facing flanges 18b formed on the sides of the webs 18d, are adapted to support and maintain in position expansion springs 18e in conjunction with flanges 18f on the webs 18d. The upper and lower webs 18d on their outer faces bear against the nailing strips and ends of the studding 14 respectively. It is to be understood that, as shown in Fig. 6, each of the studs 14 is supported at opposite ends by an expansion member 18 which in turn is held in assembled position relative to the studding and to the nailing strips by the guideways 17 within which the expansion member may move to impart resilience in a vertical plane to the studding.

Each of the studs 14 is preferably a channel shaped member formed of sheet metal from the web 14a of which, at suitably spaced intervals, 45 is stamped out pairs of oppositely directed fingers, one pair 14c facing and lying parallel to the flanges 14f of the stud and the other pair 14b lying in the same plane as the first pair but facing in an opposite direction. The fingers preferably are spaced from the flanges a distance equal to the thickness of the surfacing units 20.

Each flange 14f of the studs 14 has stamped therefrom outwardly, with respect to the wall, directed hooks 14h located at suitably spaced 55

intervals, certain of which are adapted to receive clips 21. Each of the clips 21 is in the shape of a broadened and flattened U with outwardly extending flanges 21a on the open end. The base 5 21b of the clip seats within the hook 14h and each of the flanged ends 21a bears against the faces of adjacent surfacing units 20 to hold them in place against the fingers 14b and 14c.

The surfacing units 20 may be of any suitable 10 material but I prefer that a unit having a metal shell be used in which is a layer of cementitious, fireproof material such as a composition of gypsum and asbestos or the like. By the use of such a metal surfaced unit I obtain a wall which 15 may be decorated in any suitable style prior to its erection and the completely finished unit erected in place.

In erecting the wall, after the studding has 20 been put into position, including horizontal studs 14 laid upon the nailing strip 11, the lower course 25 of panels is erected and clipped in position to the studding. Over the upper edges of these panels, between the studding, is fitted pieces of studding which are not attached to a support but the web 30 of which rests upon the upper edges of the panels. Next a second course of panels is erected and 35 clipped in position to the studding and similar clips are then connected to the horizontal piece of the studding material to maintain the top of 40 one course and the bottom of the adjacent course in a common plane, (see Fig. 3).

After all of the panels along one stud have 35 been erected, vertical finishing strips 26 are positioned. Each of these strips is of channel shape 45 and carries on the face of the web between the flanges straps 26a in the shape of a shortened U, which straps are spaced from the web of the strip a distance not greater than the depth of the flanges thereon. The straps 26a are spaced 50 apart a distance equivalent to the distance between several of the hooks 14h, and the straps are adapted to fit over the hooks not occupied by the clips 21 and thereby maintain the strip 26 in position over the space between the edges 55 of the surfacing units and over the clips 21 which hold the vertical edges in position.

The horizontal edges of the surfacing units 60 and the clips which hold them in position are covered by a finishing strip 27 which in outward 65 appearance is similar to the strip 26 but upon which the flanges are bent slightly inwardly (Figs. 2 and 3). The flanged edges engage a clip 25 having semicircular ends 25a but which is otherwise similar to the clips 21 and these hold the horizontal finishing strip 27 under a slight 70 spring tension and maintain it in position. It is understood that the horizontal studs 14 are also positioned over the uppermost of the panels 20 and beneath the lowermost of these panels, the 75 studs will be spaced from the ceiling and floor by the width of the nailing strips 10 and 11 respectively. Such spacing will permit the positioning of the finishing strips 27 as cornice and 80 base strips in the same manner as they are positioned intermediate the ceiling and floor. Should 85 it be found that the finish of the strips 27 is not esthetically desirable when they are used as either

cornice or base strips other designs may be provided by simply welding a desired shape to the strip 27 prior to the time that it is erected.

It will be obvious from a consideration of the 5 above that a space will be left between the surfacing units forming the walls of adjacent rooms, which space may be filled with any material for the desired purpose—either soundproofing or fireproofing. A wall as above described may be 10 readily erected with a hammer and level as the only tools and if the units are provided with the desired finish prior to erection it need only take a few hours, instead of several days, to erect 15 partition walls of such size as are usually found in the modern office building and such walls, when erected may have a luxurious effect and individual finish.

Various modifications may be made in the 20 above described embodiment of my invention without departing from the spirit and scope thereof as set forth in the following claims.

What I claim is:

1. In a partition wall, vertically spaced fixed 25 supports; guideways attached to each of said supports; studding; and means for resiliently mounting 30 said studding within said guideways, said guideways preventing movement of said studding other than vertically.

2. In a partition wall vertically spaced fixed 35 supports; guideways attached to each of said supports; studding; and means for resiliently mounting 40 said studding for vertical movement within said guideways, said guideways preventing movement of said studding other than vertically.

3. A building construction unit comprising a 45 channel member; hooks on the outer face of one flange of said channel member; and fingers, oppositely projecting in pairs, on the web of said channel shaped member.

4. In an interior partition wall, studding; a 50 multiplicity of surfacing units; a plurality of 55 fingers on said studding extending in a plane parallel to the plane of the surface of the wall and spaced from said plane a distance equal to 60 the thickness of a surfacing unit; clips; finishing strips and fingers on said studding, certain of 65 said fingers holding said clips in contact with the outer face of said surfacing units and pressing the inner face thereof against said first mentioned 70 fingers, and other of said fingers holding said finishing strips in place over said clips.

5. A wall construction comprising supports; 75 studding resiliently mounted with respect to said 80 supports; surfacing units; means formed integrally with said studding to prevent the movement 85 in one direction of positioned units out of a vertical plane; clips; means on said studding cooperating with said clips to prevent the movement in another direction of said units out of a vertical plane; means for positioning the top and bottom of adjacent units with respect to each other; and means for covering said last named means and said clips, said last named means defining panels on said wall.

FREDERICK M. VENZIE.
